(57) **CLAIM**

The ornamental design for a positive airway pressure system console, as shown and described.

DESCRIPTION

FIG. 1 is a front perspective view of a positive airway pressure system console.

FIG. 2 is a back perspective view of the console illustrated in FIG. 1.

FIG. 3 is a front view of the console of FIG. 1.

FIG. 4 is a back view of the console of FIG. 1.

FIG. 5 is a first side view of the console of FIG. 1.

FIG. 6 is a second side view of the console of FIG. 1.

FIG. 7 is a top view of the console of FIG. 1; and,

FIG. 8 is a bottom view of the console of FIG. 1.

The broken lines in the drawings illustrate portions of the positive airway pressure system console that form no part of the claimed design.
